UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR AN EYELET.

SPECIFICATION forming part of **Design No. 25,832**, dated **July 28, 1896**.

Application filed November 13, 1895. Serial No. 568,856. Term of patent 14 years.

To all whom it may concern:

Be it known that I, ELEAZER KEMPSHALL, of Newton, in the county of Middlesex and State of Massachusetts, have invented and 5 produced a new and original Design for Eyelets, of which the following is a specification.

This invention relates to a new and original 10 design for eyelets; and it consists in the novel features of shape and configuration hereinabove fully described, and particularly claimed, and clearly illustrated in the drawings.

Reference is to be had to the accompanying 15 sheet of drawings, forming a part of this application, in which like characters are used to indicate like parts wherever they occur.

Figure 1 represents a perspective view showing my design. Fig. 2 represents a longitudinal sectional view thereof.

The essential feature of my design consists in a tubular-shaped body, terminating at one 20 end in an overhanging flange that is provided with apertures.

a represents the tubular-shaped body; *a'*, the overhanging flange provided with apertures *a²*. 25

I claim—

The design for an eyelet, substantially as shown and described.

In testimony whereof I have signed my name to this specification, in the presence of 30 two subscribing witnesses, this 30th day of October, A. D. 1895.

ELEAZER KEMPSHALL.
